UNITED STATES PATENT OFFICE.

GEORGE E. GRIMM, OF TOLEDO, OHIO, ASSIGNOR TO THE WILLYS-OVERLAND COMPANY, OF TOLEDO, OHIO, A CORPORATION OF OHIO.

VEHICLE DOOR.

Application filed July 5, 1923. Serial No. 649,588.

This invention relates to vehicle doors and the like, and has for one object to provide an improved hoisting mechanism for a window or door sash, being particularly adapted for 5 raising and lowering the sash or window glass for the doors of closed vehicle bodies.

A further object of the invention is to economize in the construction of the hoisting mechanism by making all or the greater portion 10 of the parts in the form of stampings, and wherever possible, connecting them with the lock board by means of portions integral either with the parts themselves, or with the lock board.

15 To these and other ends, the invention embodies certain novel features of construction and arrangement of parts, as will be herein-after more fully pointed out and claimed, it being understood that the invention is susceptible of various modifications, embodiments and arrangements to suit special or varying conditions under which the invention may be practiced.

20 A structure constituting one embodiment of the invention, is illustrated in the accompanying drawings, in which:

Figure I is an interior side elevation of a door before the upholstery is applied, with parts broken away to more clearly illustrate 30 the invention.

Fig. II is an enlarged sectional elevation taken substantially on the line II-II of Fig. I.

Fig. III is an enlarged detail vertical section illustrating the mounting for the actuating and locking portions of the hoisting mechanism.

Fig. IV is a detail plan of the actuating member shown in Fig. III, upon which the 40 hoisting and locking gears are mounted.

Fig. V is a vertical section taken on the line V-V of Fig. III.

Like reference characters illustrate corresponding parts throughout the several views 45 of the drawings.

In illustrating the present invention, I have preferably shown it applied to a vehicle door 10, including stiles 11 connected by the upper and lower rails 12 and 13 respectively, and 50 also the oppositely spaced intermediate rail members 14 and 15, as shown in Fig. II, all adapted to be connected in any desired manner. The sash or window glass 16 is suitably mounted for vertical movement in the door 55 frame, preferably between the inner and

outer vertically disposed moldings or finishing strips 17, connected by similar top and bottom transverse moldings 18 and 19, as shown in Fig. I.

The panel or lock board 20 is preferably 55 formed of stamped metal and is connected with the upright door frame members 11, as by means of the screws 21. The panel is provided along its upper edge with an outwardly turned flange 22 upon which rests the cross 60 frame member 15 of the door, and to which the flange is suitably secured as by means of screws, (not shown).

One of the important features of the invention, is the mounting of all parts of the 65 window hoisting mechanism upon the panel or lock board, including also the handle for closing the door, and applying the completed unitary structure to the door frame, simply by placing it in position thereon and driving 70 the screws for connecting it therewith. In carrying out this idea, a bracket 23 is provided with a central portion spaced from the panel and a flanged portion 23' suitably connected therewith, as by means of the rivets 75 24, or in any other desired manner. Annular flanged portions 25 and 26 are provided on the panel and bracket respectively, which form spaced bearings in which the hollow 80 rotatable shaft or actuating member 27 of the hoisting mechanism is rotatably mounted.

The actuating member carries a gear 28, preferably a stamping, which is operatively connected with the actuating member by means of a pin 29 extending through oppositely positioned slots 30 formed therein, whereby said actuating member is permitted to rotate a limited amount before it moves into driving engagement with the pin 29 of the gear 28. The gear 28 is adapted to mesh with and operate 90 a segment 31, mounted on a pivot 32 near the bottom of the panel. An arm or lever 33 for lifting the sash is rigidly secured to the segment in any desired manner, as by spot-welding, and is also connected therewith by means of the pivot pin 32.

The lever 33 carries a grooved roller 35, upon which rests the rounded edge of the sash channel 36 as shown in Fig. II. At this point, the sash carries a longitudinally extending guard plate 37 for maintaining the roller in supporting engagement with the sash, upon which it is adapted to travel when the lever is raised and lowered by the segment to elevate and lower the sash. A counter-balancing 100 105 110

spring 38 is connected at one end with an outwardly bent portion 39 of the segment, and at the other end with a downwardly bent lip 40, preferably integral with the flange 22 of the door board and having a series of apertures 41, in any one of which the end of the spring may be secured, depending upon the tension required to properly balance the sash.

The rotatable actuating member 27 is provided with a crank handle 42, which is non-rotatable relative to the actuating member, and which is held against longitudinal movement thereon by a set-screw 43. The actuating member is provided with oppositely positioned longitudinal slots 44 adapted to receive correspondingly disposed ribs 45, preferably cast integral with the crank handle on the inner wall of the socket portion thereof, in which the end of the actuating member is disposed, thus affording a driving connection between the handle and actuating member and relieving the strain on the set-screw 43.

The means for automatically locking the hoisting mechanism whenever rotation of the crank handle is discontinued, comprises a gear 46, or its equivalent, normally held against rotation by any suitable stop, such as the rack 47 riveted or otherwise secured to the inner face of the bracket 23. The gear is automatically returned to locking engagement with the rack or stop by a spring 48 interposed between said gear and the gear 28 for actuating the segment 31. It is necessary of course upon initial rotation of the crank handle and before rotation of the actuating gear 28 is begun, to first release the locking mechanism. For this purpose, the gear 46 has a driving pin 49 extending through the flanged hub portion thereof and through the oppositely positioned cam grooves or slots 50 in the actuating member 27, the slots having cam faces 51 in contact with the driving pin 49. Consequently, upon rotation of the actuating member in either direction, the cam faces 51 will slide the locking gear 46 to the right, as viewed in Fig. II, thus moving it out of locking engagement with the stop or rack 47. At about this time, the actuating member 27 will have been rotated to the limit of its movement before contacting with the pin 29 in the slot 30 thereof, and upon engaging the pin, rotation of the gear 28 will begin, thereby effecting movement of the sash either up or down, depending upon the direction in which the crank handle is turned. As soon as rotation of the handle is discontinued, the spring 48 will automatically slide the gear or locking member 46 back into engagement with the rack 47, thus holding the sash at the desired elevation.

If found desirable, one or more idler gears (not shown), may be interposed between the driving gear 28 and the segment 31, thus permitting the actuating member 27 and the crank handle thereon to be located at the most

desirable position convenient for the occupant of the vehicle.

While the construction herein shown and described is well adapted to fulfill the objects primarily stated, it is to be understood that changes in the form, proportions, arrangement of parts and details of construction, may be resorted to when found expedient, without departing from the spirit of the invention as expressed in the claims.

I claim as my invention:

1. In a window lift, a rotatable actuating member operating the lift having a cam formed thereon, means for preventing endwise movement of said member, a locking device for said member longitudinally slideable upon said member and having a portion engaging said cam, whereby the locking device is automatically released during initial rotation of said member.

2. In a window lift, a rotatable actuating member operating the lift having a cam groove therein, means to prevent endwise movement of said member, a locking device for said member movable longitudinally of said member and having a portion disposed within said cam groove, whereby the locking member is automatically released upon initial rotation of the actuating member, and means for automatically resetting the locking device when rotation of the actuating member is discontinued.

3. In a window lift, a rotatable actuating member, a gear carried thereby and rotatable therewith, means to prevent endwise movement of said member, a second gear carried by said member, a stop normally engaging the second gear and forming a lock for the actuating device, said actuating device being adapted to withdraw said second gear from engagement with the stop upon initial rotation thereof, and means for automatically resetting said second gear in engagement with the stop to lock the actuating member when rotation is discontinued.

4. In a window lift, a rotatable actuating member having a transversely arranged slot therein and a gear upon said actuating member having a driving portion disposed within the slot and permitting a limited movement of the actuating member before co-operating therewith to drive said gear, a cam groove formed in said actuating member, a stop, a locking member engaging the stop and forming a lock for the actuating member, said locking member having an operative portion disposed within the cam groove whereby it is moved to release position before driving engagement is effected between said gear and the driving portion therefor, and means for resetting the locking member when operation of said actuating member is discontinued.

In testimony whereof, I affix my signature.
GEORGE E. GRIMM.
